UNITED STATES PATENT OFFICE.

WILLIAM DOHERTY, OF WEST PHILADELPHIA, PENNSYLVANIA.

ELECTRIC AIR-HEATING FURNACE.

Application filed September 27, 1926. Serial No. 138,012.

This invention relates to heating apparatus, particularly to heaters of the electrically operated type, and has for its object the provision of a novel furnace or heating device 5 adapted for household or other use for the purpose of heating air which may be distributed to a plurality of rooms or other places to be heated.

An important object of the invention is to 10 provide a heating device of this character provided with a peculiarly constructed and arranged heating unit of resistance material capable of developing a high degree of heat upon passage of an electric current there- 15 through.

A further object is to provide a heater of 20 this character having a novel construction of walls whereby the heat will be conserved and prevented from becoming dissipated into the atmosphere.

An additional object is the provision of a device of this character which will be comparatively simple and inexpensive to manufacture, and assemble, easy to control or operate, positive in action, efficient and durable in service, and a general improvement in the art.

With the above and other objects and advantages in view, the invention consists in the 25 details of construction, the arrangement and combination of parts to be hereinafter more fully described and claimed, and illustrated in the accompanying drawings, in which:

Figure 1 is a vertical sectional view taken 30 through the heater.

Figure 2 is a similar view taken at right angles to Figure 1.

Figure 3 is a horizontal cross sectional view taken on the line 3—3 of Figure 1.

Figure 4 is a detail sectional view taken 40 on the line 4—4 of Figure 2.

Referring more particularly to the drawings, I have shown the device as comprising a casing designated generally by the numeral 45 10, this casing being preferably, though not necessarily, of cylindrical shape and provided with an arched or crowned roof 11 and a base or bottom 12. While it is conceivable that the exact construction of this casing, 50 roof and base may be varied within quite wide limits, it is preferable that the bottom or base 12 be constructed of concrete, the roof or top of the same material, and the side portions or main body 10 either of concrete or other cementitious material or else of layers of asbestos or other heat resisting material indi-

cated at 13, between which is a preferably metallic shell 14. In the present instance, I have illustrated bands 15 extending horizontally about the body of the structure for 60 reinforcing purposes, certain of these bands being located at the outside and others being located at the inside, the entire purpose being to make a strong and rigid structure capable of withstanding severe temperature changes 65 without danger of buckling or disintegration. Obviously, other specific details of construction may be resorted to if found advisable inasmuch as there is no particular limitation desired in this respect. It is of course necessary that the casing be provided with means whereby access may be had to the interior thereof, and for this reason there is shown an opening 16 at some convenient point in one side, this opening being closed by a preferably 70 hinged door structure 17 of the same general characteristic as the casing construction itself, the door being provided with suitable latch means indicated at 18 for the purpose of holding it normally closed. 75

Located within the central lower portion of the casing 10 is a chamber 19 which may be formed by forming an upstanding cylindrical wall 20 upon the base or bottom 12 and extending through one side of the casing 10 80 and communicating with the chamber 19 is a cold air inlet pipe 21 of any ordinary or preferred construction preferably provided with a damper or valve 22 capable of manual or other manipulation for the purpose of regulating the inflow of fresh air to be heated. Extending into and leading from the upper portion of the casing 10 is any desired number of outlet pipes 23 which, if the device is used 85 in a dwelling house, would naturally lead to the different rooms to be heated. The length and arrangement, as well as the size of these pipes 23 is immaterial as many variations may be resorted to. Clearly, if any such means is desired, valves or the like may be 90 interposed in the air outlet pipe 23 for the purpose of controlling the passage of heated air from the casing. 95

Mounted upon the upper end of the cylindrical wall structure 20 which defines the 100 chamber 19 is a metallic plate 24 which preferably has a depending flange portion 25 embracingly engaging about the cylindrical wall 20 and which also has an upstanding flange 26 constituting retaining means for a mass 105 of disk-like form, of refractory material such as fire clay or the like. The metal disk 24 110

and the material 27 are both formed with registering holes 28 and 29 respectively, so that air entering the chamber 19 through the pipe 21 may pass upwardly and into the upper portion of the casing.

The heating means comprises a plurality of upright serpentine bar members 30 of suitable resistance metal mounted on top of the refractory member 27 by any suitable means, it being preferable that these members be spaced apart by blocks 31 of suitable insulating and refractory material held in assembled relation as by stays or bolts 32. In the present instance there are three groups of 10 serpentine resistance bars or members 30 disclosed all connected in parallel by branch conductors 33 and 34 connected with main conductors 35 and 36 respectively which lead to and through an insulated bushing 37 extending through the side of the casing 10. Obviously, any switch device may be connected with these conductors for cutting off the supply of current thereto and it is conceivable that resistance means be employed 20 for regulating the quantity of current passing through the resistance bars or elements 25 30.

In the operation of the device, it will of course be apparent that when current is fed to the resistance elements 30 they will become hot and in fact incandescent, their heat being communicated to the blocks 31 of refractory insulating material, the whole mass being very hot. The air entering 35 through the pipe or conduit 21 into the chamber 19 passes through the registering holes 28 and 29 and up through and between or among the heating units or resistance elements 30, the air being consequently heated 40 and being then discharged through the pipe 23 to the various rooms in the building to be heated. It is really believed that the construction, operation and advantages of this portion of the apparatus will be readily apparent to one skilled in the art without further explanation. However, it is of course apparent that some means must be provided for supplying current to the device and in Figures 5 and 6 I have illustrated a very convenient battery structure of the plunger type 45 which may be used in case house current is not available.

From the foregoing description and a study of the drawings, it will be readily apparent that I have thus provided a very simply constructed and inexpensive air heating device which is well adapted for use in heating dwelling houses or other places employing the hot air system. Furthermore, 50 it will be noted that I have also disclosed a

very simply constructed, inexpensive and yet highly efficient plunge battery for the purpose of supplying current to the heating elements. It is really believed that the construction, operation and advantages will be 65 readily apparent to one skilled in the art without further explanation.

While I have shown and described the preferred embodiment of the invention, it should be understood that I reserve the right to 70 make such changes in the form, construction and arrangement of parts as will not depart from the spirit of the invention or the scope of the subjoined claims.

Having thus described the invention, I 75 claim:

1. In a heater of the character described, a casing provided near its top with a plurality of radially extending outlet pipes, an upstanding chamber member within the central lower portion of the casing, a cold air inlet pipe extending thru one side of the casing into said chamber member, a metal cover on said chamber member having a plurality of holes therein, a refractory top on said cover having holes registering with said first named holes, and heating means mounted above and supported upon said chamber structure and including a serpentine resistance member arranged in upright position 80 and secured upon said refractory top with its alternate convolutions located above and registering with said holes.

2. In a heater of the character described, a casing provided near its top with a plurality of radially extending outlet pipes, an upstanding chamber member within the central lower portion of the casing, a cold air inlet pipe extending thru one side of the casing into said chamber member, a metal cover 95 on said chamber member having a plurality of holes therein, a refractory top on said cover having holes registering with said first named holes, and heating means mounted above and supported upon said chamber structure and including a serpentine resistance member arranged in upright position 100 and secured upon said refractory top with its alternate convolutions located above and registering with said holes.

3. In a heater of the character described, a casing provided near its top with a plurality of radially extending outlet pipes, an upstanding chamber member within the central lower portion of the casing, a cold air inlet pipe extending thru one side of the casing into said chamber member, a metal cover 105 on said chamber member having a plurality of holes therein, a refractory top on said cover having holes registering with said first named holes, and heating means mounted above and supported upon said chamber structure and including a serpentine resistance member arranged in upright position 110 and secured upon said refractory top with its alternate convolutions located above and registering with said holes, and spacing and confining means for the serpentine heating unit comprising a series of block-like members of refractory material recessed at their edges and interposed between the successive convolutions in such manner as to imbed 115 or enclose the convolutions between them, and stay passing thru said block-like members outwardly of the convolutions.

In testimony whereof I affix my signature.
WILLIAM DOHERTY.
